UNITED STATES PATENT OFFICE.

FRITZ MINK, OF PHILADELPHIA, PENNSYLVANIA, ASSIGNOR TO THE KEYSTONE WATCH CASE COMPANY, OF PHILADELPHIA, PENNSYLVANIA, A CORPORATION OF PENNSYLVANIA.

DESIGN FOR A PENDANT-BOW.

41,552.

Specification for Design.

Patented July 11, 1911.

Application filed May 12, 1911. Serial No. 626,861. Term of patent 7 years.

To all whom it may concern:

Be it known that I, FRITZ MINK, a citizen of the United States, and a resident of Philadelphia, in the county of Philadelphia and State of Pennsylvania, have invented a certain, new, original, and ornamental Design for Pendant-Bows, of which the following is a specification.

The accompanying drawing is a view in

side elevation of a pendant-bow having my design applied thereto.

I claim:

The ornamental design for a pendant-bow, as shown.

FRITZ MINK.
